(57) **CLAIM**

The ornamental design for an arm and wrist guard, as shown and described.

DESCRIPTION

FIG. 1 is an upper perspective view of a first embodiment of an arm and wrist guard showing my new design.

FIG. 2 is a lower perspective view of the arm and wrist guard of FIG. 1.

FIG. 3 is a top plan view of the arm and wrist guard of FIG. 1.

FIG. 4 is a bottom plan view of the arm and wrist guard of FIG. 1.

FIG. 5 is a right elevation view of the arm and wrist guard of FIG. 1.

FIG. 6 is a left elevation view of the arm and wrist guard of FIG. 1.

FIG. 7 is a front elevation view of the arm and wrist guard of FIG. 1.

FIG. 8 is a rear elevation view of the arm and wrist guard of FIG. 1.

FIG. 9 is an upper perspective view of a second embodiment of an arm and wrist guard.

FIG. 10 is a lower perspective view of the arm and wrist guard of FIG. 9.

FIG. 11 is a top plan view of the arm and wrist guard of FIG. 9.

FIG. 12 is a bottom plan view of the arm and wrist guard of FIG. 9.

FIG. 13 is a right elevation view of the arm and wrist guard of FIG. 9.

FIG. 14 is a left elevation view of the arm and wrist guard of FIG. 9.

FIG. 15 is a front elevation view of the arm and wrist guard of FIG. 9; and,

FIG. 16 is a rear elevation view of the arm and wrist guard of FIG. 9.

The broken lines depict portions of the arm and wrist guard that form no part of the claimed design.
